8 Claims. (Cl. 315—21)

1

This invention relates to a circuit-arrangement for deflecting the cathode-ray beam in a cathode-ray tube, the end of the beam describing a closed curve.

Circuit-arrangements are known with which the beam performs the aforesaid movement and the end of the beam describes, for instance, a circle, but in this case this is effected by means of suitable deflection voltages or currents supplied by separate generators.

With the circuit-arrangement according to the invention the movement of the beam is not effected by means of such separate generators but entirely automatically.

The circuit-arrangement according to the invention exhibits the feature that when the beam hits a collecting electrode within the tube, the beam current influences the deflection means in a manner such that the beam moves over this collecting electrode.

In order that the invention may be more clearly understood and readily carried into effect, it will now be described more fully with reference to the accompanying drawing, given by way of example in which

Figure 1 is in part a perspective view of parts of the cathode ray tube and in part a circuit diagram showing an illustrative embodiment of the invention.

Figure 2 is in part a plan view of a collecting electrode and in part a diagrammatic view of the circuit connections to the deflecting means in a modification of the invention.

Figure 3 is a further modification of Figure 2.

Figures 4 to 7 are partial diagrammatic views of the structure of electrodes suitable for use in a cathode ray tube constructed according to the invention.

In Figure 1 the reference numeral 1 denotes the cathode of a cathode-ray tube which is not further represented. By means known per se a cathode-ray beam 2 is formed which passes through the point 3 if no deflection occurs.

In addition the tube comprises deflection plates 4 and 5 for deflecting the beam in a horizontal direction, and a set of deflection plates (not represented) for deflection in a vertical direction. Furthermore it comprises a collecting electrode 6 which is connected to the deflection plate 4 through a lead 7. This deflection plate and the collecting electrode are connected, through a common resistance 8, to the positive terminal of a source of potential of which the negative terminal is connected to the cathode 1. The plate 5 may be directly connected to the positive terminal of the

2

source of potential so that no potential difference is set up between plates 4 and 5 if the resistance 8 is not traversed by current.

If the plates for vertical deflection receive a voltage impulse having the correct value the beam hits the collecting electrode 6 at 9. Due to this the beam-current traverses the resistance 8 and reduces the potential of the deflection plate 4 with the result that horizontal deflection in the direction of the arrow 10 occurs. If the collecting electrode 6 has a sufficient size in a horizontal direction, the end of the beam travels over this electrode until it reaches the point at which the deflection attains the value corresponding with the occurring deflection voltage. This point may, for instance, be located at 11. It is pointed out in this respect that the location of point 11 is variable, for instance by varying either the current strength of the beam or the resistance 8, and furthermore it depends upon the deflecting effect of the deflection system, consequently of the positioning and size thereof, so that the location of this point broadly depends upon the value of the back-coupling between the collecting electrode 6 and the deflection system.

In the foregoing the fact has not been taken into account that a voltage for directing the beam to the point 9 of the electrode 6 is supplied to the vertical deflection plates, it is true, but that no subsequent vertical deflecting voltage occurs. Owing to this the beam tends to return in a vertical direction to the level of point 3 so that, if the electrode 6 should have the required size also in a vertical direction, the beam would eventually not be directed to point 11 but to point 12 which, consequently, is vertically located at the same level as point 3 and exhibits horizontally the same deviation as point 11. Consequently, the beam will move over the electrode 6, viewed from point 9, in the direction of the arrow 13 to the point 12 which will be called the direction point. Naturally this direction point 12 is only reached if the electrode 6 has a sufficient size.

With each collecting electrode a given arrangement of the deflection means, a constant current strength of the beam and fixed resistance 8 corresponds to a single direction point. On hitting a collecting electrode the beam will consequently be deflected as long as the point of impact does not coincide with the direction point. In this connection it is pointed out that for deflecting the beam use may also be made of collecting electrodes constructed as a resistance electrode, but in this case the current strength in the resistance 8 will be different with every new position of the point

of impact of the beam on this electrode with the result that in every instance a different direction point corresponds thereto.

Furthermore it is not necessary to use the coupling, shown in Figure 1, between the collecting electrode and the deflection means. For instance, deflection coils may also be used which are inserted in the output circuit of the collecting electrode. Alternatively the deflection coil may be included in the output circuit of a discharge tube, this current being controlled by a voltage which is set up in the input circuit of the tube and depends upon the current strength in the circuit connected to the collecting electrode.

In the circuit-arrangement shown in Figure 2 a cathode-ray tube (not represented) comprises a collecting electrode 51 which is constructed as a collecting electrode. This electrode has an annular shape or, viewed in the direction of the cathode-ray beam, appears to have an annular shape. In the present case the expression "resistance electrode" is to be understood to mean an electrode of which the specific resistance exceeds that of the metals usually employed as electrode material. The ring may, for instance, consist of insulating material to which a layer of graphite is applied or which may entirely be made of graphite. This ring is fed from a positive supply through equal resistances 14, 15 and 16 located at three equidistant points or, if the cathode of the cathode-ray tube has a negative potential, is earthed through the intermediary of the said resistance. Furthermore three deflection plates 17, 18 and 19 are provided, the positioning of these plates being displaced by 120° with respect to the location where they are connected to the corresponding resistance. When the beam hits the resistance electrode 51, for instance at 20, which may be ensured by means of a suitable deflection voltage, a voltage variation occurs over each resistance. Owing to the fact, however, that the electrode has not a negligible but an appreciable resistance, the said voltage variation depends upon the spacing, measured along the electrode, between point 20 and the junction points of the resistances. Due to this the voltage drop across the resistance 14 has the highest value and that across the resistance 15 the lowest value. In this case the potential of the deflection plate 17 is lowest and that of plate 18 highest so that the beam experiences a deflection force by which the end of the beam is displaced over the electrode in the direction of the arrow 21, in other words each point of impact is associated with a direction point which is located before the point of impact and in the direction of the tangent of the circle to be described. If this should not be quite true, for instance at the onset of the movement at 20, so that the direction point associated with the point of impact 20 is not located on the line tangent to the circle and passing through point 20, the beam itself will choose a path having a slightly different radius so as to satisfy this requirement, and if the deviation is too large correct adjustment is ensured by varying the "phase-shift angle" of the positioning of the deflection plates with respect to their junction points.

Figure 3 represents another form of construction of the circuit-arrangement according to the invention.

In this construction the cathode-ray tube comprises a number of collecting electrodes 22 which are located in such manner that, viewed in the

direction of the beam, they follow a circle, the spacing between two successive electrodes being smaller than the diameter of the cathode-ray beam. Each electrode is connected to the junction point of two resistances 23 of which the number equals that of the electrodes and which are included in a ring connection which is fed, through resistances 24 at four points. The voltages for the deflection plates 25 in the tube are taken off at four symmetrically located points, the position of each deflection plate being displaced by more than 90° with respect to the point from which the voltage for this plate is taken. If, for instance, the pair of plates 25a is exactly at an angle of 90° with respect to points 26 and 26a, the direction point, on the beam hitting e. g. the electrode 22a, is located on a broken line, extending at right angles to the connecting line 26, 26a, so that the point of impact tends to shift in the direction of the arrow 27, the direction of which does not correspond with the line tangent to the circular path to be traversed. Fundamentally this can be improved upon by providing that the direction point on the broken line is very distant which consequently means a very high deflection voltage. On turning, however, the pair of plates 25a to the represented position, the direction point lies on the broken line 28 and in this case the location of the direction point may be such that it lies exactly in the direction of the line tangent to the circular path.

In this case, however, the difficulty is experienced that the direction point extends in the direction of the tangent, it is true, but this direction may vary under the influence of the factors referred to, for instance the current strength of the beam. Therefore, it is advisable to choose the direction point of each electrode in a manner such that it tends to urge the beam outwards or inwards under normal operating conditions. In the drawing the direction of these direction points is indicated by a broken arrow in several electrodes, which directions are consequently not tangent to the circle formed by the electrodes 22 but point outwardly. These directions result from rotation of the deflection system.

In this case a number of further electrodes 29 should be provided, of which the direction point extends in such manner that the beam, on hitting these electrodes, is urged back to the electrodes 22. This may be effected in a simple manner by connecting such an electrode 29 to an electrode 22 which has the desired direction of the direction point, for instance the electrode 22b. In this case the beam will pass over the outer edge of the system 22. In the case of possible small variations of the working conditions the movement of the beam will not be affected.

Furthermore it will be appreciated that the direction points of the electrodes 22 may also be such that the beam will describe a smaller circle, in which case other electrodes 30 are provided at the inner side, which cause the beam to pass over the inner wall of the system 22.

The electrodes 29 may, for instance, be partly provided behind the electrodes 22 and at the interstice between two electrodes 22 they may be provided with recesses 29a for purposes which will be explained hereinafter.

It is pointed out that in this kind of circuit-arrangements it is not necessary for the end of the beam to describe a circular path, since any other closed curve may be followed, provided that the deflection means are suitably positioned and

the coupling of the electrodes to the deflection means is accommodated to the electrode arrangement in such manner that the deflection means are steadily influenced in the desired manner.

Furthermore the electrodes in a circuit-arrangement as shown in Figure 3 need not be arranged in a manner such that, viewed from the cathode, they are interspaced since they may in part also be positioned one behind the other.

Alternatively the electrode arrangement may be such as to form two curves which are closed in themselves and have a common part. If the beam passes over this common part a choice may be made at the end thereof which of the two curves will be followed. The principle of such a circuit-arrangement will be explained with reference to Figure 4.

The electrodes 32, 33, 34, 35 form part of a system in which the beam is adapted to follow a closed curve, the same holding for the electrodes 32, 33, 36, 37. If the end of the beam rests on the electrode 32 the beam moves to the right, according to the arrow, and hits the electrode 33. The direction point associated with this electrode lies on the line 38, 39, 40, the point 40 being the point at which the beam is not deflected so that it corresponds to the point 3 shown in Figure 1. If in the circuit-arrangement shown in Figure 1 the current-strength of the beam is doubled, as result of which the voltage drop across the resistance 8 is doubled, the final position of the beam, which corresponds with the said increase in deflection voltage, may, for instance, be 11^a. Thus the direction point 12^a ensues. This is utilised in the circuit-arrangement shown in Figure 4.

At a given value of the current-strength of the beam the direction point is located at 38 so that the beam travels from the electrode 33 to the electrode 35, and at a different value of the current strength of the beam the direction point 39 ensues so that the beam travels from the electrode 33 to the electrode 36.

Various arrangements are possible for reversing the direction of travel of the beam on hitting a collecting electrode. By means of such arrangements the beam may at the same time be immobilised.

The latter may, for instance, be effected, in a circuit-arrangement as shown in Figure 3 by interrupting the connection between any of the collecting electrodes and the ring connection of resistances and by connecting this electrode to the diametrically opposite point in the ring connection. On hitting this electrode the direction of travel reverses so that the beam adjusts itself to the edge of this electrode and to the edge of the electrode traversed last.

In this respect it is pointed out, however, that if the direction point e. g. of the electrode 22^a is located on the line tangent to the circular path i. e. on the broken line 28, a direction point 31 is produced, likewise on the line 28 but at the other side of the centre point, on detaching this electrode from the ring connection and connecting it to the diametrically opposite point of the ring connection. In this case it is possible for this new direction not to intersect the adjacent electrode 22^c so that immobilisation does not occur.

If the direction point 31 is located at a sufficient distance, for instance in the case of using the outer direction points, the beam does hit the electrode 22^c.

Alternatively a number of electrodes 30 may be provided for this purpose, which tend to urge the

beam outwardly, so that in this case the electrode 30 located at the electrodes 22^a and 22^c may be directly connected to the electrode 29.

It is also possible to reverse the direction of travel if the collecting electrodes are secondary-emission electrodes and at least at one of the collecting electrodes a further electrode is provided to which a suitable voltage is supplied for suppressing the secondary-emission of the associated collecting electrode. Such a circuit-arrangement will be explained with reference to Figures 3, 5 and 6.

If all the collecting electrodes of the circuit-arrangement shown in Figure 3 are secondary-emission electrodes, the voltage variation, upon the beam hitting an electrode, will be opposite to that in the case of non-secondary-emission electrodes so that the direction of travel is exactly opposite to the direction of the arrow. At one or more of the electrodes 22 shown in Figure 3, for instance at the electrode 41 shown in Figure 5, there is provided a grid-shaped electrode 42 and this more particularly between the incident direction of the cathode-ray beam 43 and the electrode 41.

If the beam hits the electrode 41 while the electrode 42 has a slightly higher potential than 41, secondary emission occurs and the direction of travel remains unchanged. If, however, the grid receives a potential which is sufficiently negative with respect to the potential of the electrode 41, the secondary emission is suppressed and the direction of travel is reversed so that the beam is immobilised as depicted in Figure 6, when the beam 43 hits partly the electrode 44 and partly the electrode 45.

If all electrodes are provided with an associated electrode the direction of travel of the beam can be reversed completely.

The circuit-arrangement shown in Figure 5 may, for instance, be used as a call-finder in automatic telephony systems. The beam steadily rotates over the electrodes until a subscriber takes the receiver from his apparatus and thus causes the voltage of an electrode 42 to drop so that the beam is immobilized in a definite position. That part of the beam passing between the electrodes 44 and 45 in Figure 6, may now be used as a telephony channel if this beam portion falls on a suitably positioned collecting electrode.

If the beam is adjusted to the edge of the electrode system, which is possible e. g. in the circuit-arrangement shown in Figure 3, it is advantageous to provide the electrode 29 with recesses 29^a so that the passing part of the beam is not or substantially not intercepted.

Finally Figure 7 represents diagrammatically another circuit-arrangement, in which reversal of the direction of travel and consequent immobilisation of the beam is likewise ensured. In this case also a number of electrodes are arranged and connected to the deflection means in such manner that the beam travels from one electrode to the other.

If not deflected the beam may for instance, reach the point 47, the direction point associated with the electrode 46 lying on the line 49, 48, 47.

In accordance with the current strength of the beam this direction point may now, for instance, occupy the position 48 or 49.

When the beam travels from the electrode 50 to the electrode 46 and the current strength is such that the direction point is located at 48, the beam passes on to the electrode 51. If, however, the direction point is located at 49, the

direction of travel is reversed and the beam adjusts itself to the edges of the electrodes 50 and 46.

What I claim is:

1. A cathode-ray deflection circuit arrangement comprising a source of cathode-rays having a given free path, a target system displaced from the said free path and charged with respect to the said source of cathode rays, a plurality of deflection elements having given fields about the 10 said cathode-rays, and resistive means to couple the said deflection elements to articulate points on the said target system, said latter resistive means having values at which the said attraction of the target system has an angular coplanar relationship to the said fields of the deflection devices.

2. A cathode-ray deflection circuit arrangement comprising a source of cathode-rays having a given free path and diameter, a target system having a plurality of circumferentially arranged collecting electrodes spaced a distance less than the diameter of the said cathode-rays and vectorially displaced from the free path of said cathode-rays, a plurality of resistance elements connected individually between the said successive collecting electrodes to form a resistance mesh, an accelerating voltage supplied to the said target system through the said resistance mesh, a plurality of deflection elements having given fields, and means to join said deflection elements severally to an equal number of symmetrically located points on the said resistance mesh, said resistance elements having values at which the vectorial displacement of the free path of the cathode-rays and the target system has an angular, coplanar relationship to the fields of the said deflection elements.

3. A cathode-ray deflection circuit arrangement comprising a source of cathode-rays having a given free path and diameter, a first target system having a plurality of circumferentially arranged collecting electrodes spaced a distance less than the diameter of the said cathode-rays and vectorially displaced from the free path of said cathode-rays, a plurality of resistance elements connected individually between successive collecting electrodes of the said first target system to form a resistance mesh, an accelerating voltage supplied to the said first target system through the said resistance mesh, a plurality of deflection elements having given fields, means to join said deflection elements severally to an equal number of symmetrically located points on the said resistance mesh, said resistance elements having values at which the vectorial displacement of the free path of the cathode-rays and the target system has an angular, coplanar relationship to the fields of the said deflection elements, an auxiliary target system having a plurality of collecting electrodes circumferentially adjacent to the collecting electrodes of the said first target system and means to couple electrically the said collecting electrodes of the said auxiliary target system to given points on the first target system at which the said cathode-rays will travel along the edge of the collecting electrodes of the said first target system.

4. A cathode-ray deflection circuit arrangement comprising a source of cathode-rays having a given free path and diameter, a target system having a plurality of collecting electrodes arranged to form a closed curve, said collecting electrodes spaced a distance less than the diameter of the said cathode-rays and vectorially displaced

from the free path of said cathode-rays, a plurality of resistance elements connected individually between successive collecting electrodes of the said target system to form a resistance mesh, an accelerating voltage supplied to the said target system through the said resistance mesh, a plurality of deflection elements having given fields, and means to join said deflection elements severally to an equal number of symmetrically located points on the said resistance mesh, said resistance elements having values at which the vectorial displacement of the free path of the cathode-rays and the target system has an angular, coplanar relationship to the fields of the 15 said deflection elements.

5. A cathode-ray deflection circuit arrangement comprising a source of cathode-rays having a given free path and diameter, a target system having a plurality of circumferentially arranged collecting electrodes spaced a distance less than the diameter of the said cathode-rays and vectorially displaced from the free path of said cathode-rays, a plurality of resistance elements connected individually between successive collecting electrodes of the said target system to form a resistance mesh, an accelerating voltage supplied to the said target system from the said resistance mesh, a plurality of deflection elements having given fields, means to join said deflection elements severally to an equal number of symmetrically located points on the said resistance mesh, said resistance elements having values at which the vectorial displacement of the free path of the cathode-rays and the target system has an angular, coplanar relationship to the fields of the 20 said deflection elements.

25 6. A cathode-ray deflection circuit arrangement comprising a source of cathode-rays having a given free path and diameter, a target system having a plurality of collecting electrodes arranged to provide at least two closed curves, said collecting electrodes spaced a distance less than the diameter of the said cathode-rays, vectorially displaced from the free path of said cathode-rays and having at least one electrode common to each closed curve, a plurality of resistance elements connected individually between the said successive collecting electrodes, to form a resistance mesh, an accelerating voltage supplied to the said target system from the said resistance mesh, a plurality of deflection elements having given fields, means to join said deflection elements severally to an equal number of symmetrically located points on the said resistance mesh, said resistance elements having values at which the vectorial displacement of the free path of the cathode-rays and the target system has an angular coplanar relationship to the fields of the said deflection elements, and means to energize at least one of the said deflection elements to divert the said cathode-rays to each of the closed curves of the 30 said target system selectively.

65 7. A cathode-ray deflection circuit arrangement comprising a source of cathode-rays having a given free path and diameter, a target system having a plurality of circumferentially arranged collecting electrodes spaced a distance less than the diameter of the said cathode-rays and vectorially displaced from the free path of said cathode-rays, at least one of the collecting electrodes of the said target system having an auxiliary electrode, means to provide a voltage to the said 75

auxiliary electrode to control the secondary emissivity of the said one collecting electrode, a plurality of resistance elements connected individually between successive collecting electrodes of the said target system to form a resistance mesh, an accelerating voltage supplied to the said target system from the said resistance mesh, a plurality of deflection elements having given fields, and means to join said deflection elements severally to an equal number of symmetrically located points on the said resistance mesh, said resistance elements having values at which the vectorial displacement of the free path of the cathode-rays and the target system has an angular, coplanar relationship to the fields of the said deflection elements.

8. A cathode-ray tube comprising a source of cathode-rays, a collecting electrode circumferentially arranged and vectorially displaced from the free path of the said cathode-rays, said collecting electrode having a given resistive gradient upon traverse, a plurality of equally spaced taps upon the said collecting electrode, means to supply the said tap points with a source of accelerating potential, a number of deflecting elements equal to

the number of said collecting electrode taps having given fields, and means to couple the said collecting electrode taps to the said deflecting elements, the said deflecting elements having an orientation with respect to the said collecting electrode taps at which the vectorial displacement of the free path of the cathode-rays and the collecting electrode has an angular, coplanar instantaneous relationship to the fields of the deflecting elements.
